UNITED STATES PATENT OFFICE.

WILLIAM L. MCGRATH, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,396,519.

Specification of Letters Patent.

Patented Nov. 8, 1921.

Application filed November 17, 1919. Serial No. 338,690.

To all whom it may concern:

Be it known that I, WILLIAM L. MCGRATH, a citizen of the United States, residing at Elmira, in the county of Chemung and State 5 of New York, have invented certain new and useful Improvements in Engine-Starters, of which the following is a specification.

My invention relates to a starter for starting an engine such as an internal combustion engine and the object thereof is to provide certain improvements in the particular type of starter drive illustrated and described in my application for patent filed 15 October 21st, 1919, Serial No. 332,193. This drive is of the well-known Eclipse-Bendix type characterized by a rotatable member such as a screw shaft and a driving member such as a pinion automatically controlled in 20 its movements by such shaft whereby when the prime mover such as an electric motor is operated the pinion is automatically meshed with the engine member such as the fly wheel thereof, and is automatically demeshed therefrom by reason of the greater 25 speed of the engine. My improvements relate to means for facilitating the meshing operation and for retaining the parts in demeshed position, particularly when such 30 parts are rotating after the engine has been started.

In the drawing Figure 1 is an elevation partly in section of a drive embodying my invention and Fig. 2 a cross-section on the 35 line 2—2 of Fig. 1.

Inasmuch as my present invention consists of an improvement engrafted upon the construction shown in my patent application aforesaid, I employ the same reference character for the same parts.

The gear 3 is driven by an electric motor, not shown and is secured by the key 4 to one end of the casing or cylinder 5. The inner end of this cylinder is supported by a 45 collar or driving head revolving around stationary shaft 8 extending the full length of the cylinder and also therebeyond at the right-hand end where it is supported in a bracket 9. This shaft is held in position in 50 this bracket by the nut 11.

The drive proper which is contained within cylinder 5 comprises a driving head consisting of the flange 12 and hub 13 mounted loosely upon shaft 8. The flange is inter-

locked at its edge to the cylinder 5, such 55 parts being held in place by screw ring 14.

The driving head is connected by the coiled drive spring 15 with a driven head 16 of the hollow screw shaft 17, mounted loosely upon shaft 8. The drive spring is 60 anchored to the driving and driven heads by studs 18 and 19 respectively. The screw shaft is provided with the usual stop nut 20.

The driving member which is adapted to engage the fly wheel 21 comprises a pinion 65 22 mounted loosely upon the extreme outer end of shaft 8 and a cylindrical extension or shell 23 projecting inwardly and over the screw-threaded portion of shaft 17. This shell is internally screw-threaded so as to co- 70 operate with the screw threads of shaft 17. In the present instance these screw threads of the shell are formed separately, the same being formed in the inner bore of the sleeve 24 having an annular flange 25 interlocked 75 with the inner or right-hand end of shell 23 and secured together by the screw ring 26.

In the annular or disk portion 37 connecting the pinion body and the shell 23, I provide means for facilitating the meshing of 80 the pinion and fly wheel and for retaining the drive parts in demeshed position. As shown such means consists of a plurality of pins 38 arranged in radial bores 39 in the disk portion 37 of the pinion structure. 85 These pins are of less length than their bores and are speed controlled inasmuch as at least one of them at a time bears by gravity against the shaft 8 and all slide outwardly by centrifugal force when the pinion is ro- 90. 90.

The inner ends of these pins are somewhat pointed and adapted to engage when in their innermost position with longitudinal grooves 40 of the predetermined length as shown in Fig. 1 toward the outer 95 end of the shaft 8. When the pinion is at rest the upper one or more of these pins contacts with the shaft and takes its position in a groove presented to it. The cylinder 5 is provided with an inner annular inclined 100 shoulder 41 with which the outer ends of these pins coöperate in the demeshing operation in the manner hereinafter explained in describing the operation of the drive.

Describing a cycle of operation, when the 105 motor is started the gear 3 will be rotated. As a result the entire cylinder 5 and the driving heads and screw shaft therewithin

will be rotated around the stationary shaft 8 as an axis and as a support. The pinion 22 will thereupon be advanced longitudinally of the screw shaft and into mesh with 5 the fly wheel gear. The screw threads of the shaft 17 and sleeve 24 are loosely fitted and the pinion 22 is likewise loosely fitted upon the extreme reduced diameter end of the shaft 8 so that the weight of the pinion 10 and its shell bears upon the upper surface of the stationary shaft sufficiently to cause friction to retard or prevent any tendency of the pinion to rotate at this time, which in addition to its inertia insures the desired 15 longitudinal movement thereof. The pinion continues to advance longitudinally until the screw sleeve 24 comes into contact with the stop nut 20, whereupon such pinion will partake of the rotary movement of the screw 20 shaft and will thereby rotate the fly wheel. When the engine starts on its own power the pinion will be automatically demeshed and returned to normal position in the well-known manner.

25 The foregoing describes the operation without reference to the improvements forming the subject matter of this application whose operations and functions will now be explained. When the parts are in normal 30 position one or more of the pins are contacting the stationary shaft in one or more of its grooves, which contact tends to prevent the rotation of the pinion and thus assists in enforcing mesh of the pinion with the fly wheel. The lower one or more of these pins contact the cylinder 5 but being very light in weight they readily ride over the inclined shoulder 41 when the pinion is advanced longitudinally toward the fly wheel. The 35 grooves 40 are preferably of such length that the pins will have reached the plain surface of the shaft 8 by riding out of the end of the grooves by the time that the pinion engages the fly wheel and is ready to rotate.

40 When the pinion is demeshed from the fly wheel, it is of course rotating at a very high rate of speed, and under the centrifugal effect all of the pins are thrown toward the periphery of the disk 37 and thus contact 45 with the cylinder 5. This centrifugal action causes the pins to contact such cylinder with sufficient pressure to prevent them from riding up the inclined shoulder 41 and thus assist in retaining the parts in demeshed 50 position while rotating.

I claim:

1. An engine starter drive including a 55 rotatable member, a driving member mounted thereon for rotary movement thereof and longitudinal movement therewith to engage a part of the engine to be started and means contained within such driving member normally operative to hold such latter member against rotary movement to enforce its longitudinal movement and operative to hold it

retracted when rotating in disengaged position.

2. An engine starter drive including a rotatable member, a driving member mounted thereon for rotary movement thereof and longitudinal movement therewith to engage a part of the engine to be started, and means contained within such driving member normally operative to hold such latter member against rotary movement to enforce its longitudinal movement and operative to hold it retracted when rotating in disengaged position, said means being controlled by the speed of the driving member. 70 75

3. An engine starter drive including a rotatable member, a driving member mounted thereon for rotary movement thereof and longitudinal movement therewith to engage a part of the engine to be started, and means contained within such driving member normally operative to hold such latter member against rotary movement to enforce its longitudinal movement and operative to hold it retracted when rotating in disengaged position, said means consisting of a plurality of radially movable pins mounted in such driving member. 80 85

4. An engine starter drive including a rotatable member, a driving member mounted thereon for rotary movement thereof and longitudinal movement therewith to engage a part of the engine to be started, and means contained within such driving member normally operative to hold such latter member against rotary movement to enforce its longitudinal movement and operative to hold it retracted when rotating in disengaged position, said means consisting of a plurality of radially movable pins mounted in such driving member and an element extraneous of the driving member engaged by the pins when such latter member is rotating in disengaged position. 95 100 105

5. An engine starter drive including a rotatable member, a driving member mounted thereon for rotary movement thereof and longitudinal movement therewith to engage a part of the engine to be started, and means normally controlled by gravity to hold such latter member against rotary movement to 110 enforce its longitudinal movement. 115

6. An engine starter drive including a rotatable member, a driving member mounted thereon for rotary movement thereof and longitudinal movement therewith to engage a part of the engine to be started, and means normally controlled by gravity to hold such latter member against rotary movement to enforce its longitudinal movement, and controlled by centrifugal force to hold such member retracted when rotating in disengaged position. 120 125

7. An engine starter drive including a rotatable shaft, a supporting shaft therefor, a driving member mounted on the ro- 130

- 5 tatable shaft for longitudinal movement thereof and rotary movement therewith, and also supported by such supporting shaft, and means coöperating with the driving member and with such supporting shaft to normally hold the driving member against rotary movement to enforce its longitudinal movement.
- 6 8. An engine starter drive including a rotatable shaft, a supporting shaft therefor, a driving member mounted on the rotatable shaft for longitudinal movement thereof and rotary movement therewith, and also supported by such supporting shaft, and means coöperating with the driving member and with such supporting shaft to normally hold the latter member against rotary movement to enforce its longitudinal movement, and also coöperating with such driving member to hold it retracted when rotating in disengaged position.
- 10 9. An engine starter drive including a rotatable shaft, a supporting shaft therefor, a driving member mounted on the rotatable shaft for longitudinal movement thereof and rotary movement therewith and also supported by such supporting shaft, and a plurality of pins radially mounted in the driving member, one or more of which pins is adapted to engage the supporting shaft to enforce longitudinal movement of the driving member when the rotatable shaft is rotated.
- 15 10. An engine starter drive including a rotatable shaft, a supporting shaft therefor, a driving member mounted on the rotatable shaft for longitudinal movement thereof and rotary movement therewith and also supported by such supporting shaft, and a plurality of pins radially mounted in the driving member, one or more of which pins is adapted to engage the supporting shaft to enforce longitudinal movement of the driving member when the rotatable shaft is rotated, in combination with means extraneous of the driving member engaged by the pins when acted on by centrifugal force to thereby hold such member retracted when rotating in disengaged position.
- 20 11. An engine starter drive including a rotatable shaft, a supporting shaft therefor, a driving member mounted on the rotatable shaft for longitudinal movement thereof and rotary movement therewith and also supported by such supporting shaft, a cylinder inclosing said drive and means coöperating with such supporting shaft and with the driving member to enforce longitudinal movement of the latter and with such cylinder to hold the driving member retracted when rotating in disengaged position, said means being speed controlled.
- 25 12. An engine starter drive including a rotatable shaft, a supporting shaft therefor, a driving member mounted on the rotatable shaft for longitudinal movement thereof and rotary movement therewith and also supported by such supporting shaft, a cylinder inclosing said drive and means coöperating with such supporting shaft and with the driving member to enforce longitudinal movement of the latter and with such cylinder to hold the driving member retracted when rotating in disengaged position, said means consisting of a plurality of pins mounted for radial movement in the driving member to engage the supporting shaft by reason of gravity and the cylinder by reason of centrifugal force.
- 30 13. An engine starter drive including a rotatable shaft, a supporting shaft therefor, a driving member mounted on a rotatable shaft for longitudinal movement thereof and rotary movement therewith and also supported by such supporting shaft, a cylinder inclosing said drive and means coöperating with such supporting shaft and with the driving member to enforce longitudinal movement of the latter and with such cylinder to hold the driving member retracted when rotating in disengaged position, said means consisting of a plurality of pins mounted for radial movement in the driving member to engage the supporting shaft by reason of gravity and the cylinder by reason of centrifugal force.
- 35 14. An engine starter drive including a rotatable shaft, a supporting shaft therefor, a driving member mounted on a rotatable shaft for longitudinal movement thereof and rotary movement therewith and also supported by such supporting shaft, a cylinder inclosing said drive and means coöperating with such supporting shaft and with the driving member to enforce longitudinal movement of the latter and with such cylinder to hold the driving member retracted when rotating in disengaged position, said means consisting of a plurality of pins mounted for radial movement in the driving member to engage the supporting shaft by reason of gravity and the cylinder by reason of centrifugal force, said cylinder having an interior inclined shoulder behind which the pins are positioned when coöperating therewith.
- 40 15. An engine starter drive including a rotatable shaft, a supporting shaft therefor, a driving member mounted on the rotatable shaft for longitudinal movement thereof and rotary movement therewith and also supported by such supporting shaft, and a plurality of pins radially mounted in the driving member, one or more of which pins is adapted to engage the supporting shaft to enforce longitudinal movement of the driving member when the rotatable shaft is rotated, said supporting shaft having a plurality of longitudinal grooves normally engaged by the pins.
- 45 16. An engine starter drive including a rotatable shaft, a supporting shaft therefor, a driving member mounted on the rotatable shaft for longitudinal movement thereof and rotary movement therewith and also sup-

- ported by such supporting shaft, said driving member comprising a pinion mounted to slide on the supporting shaft, a hollow extension mounted on the rotatable shaft, and 5 a disk portion intermediate such pinion and extension, and means mounted in such disk portion and coöperating with said supporting shaft to enforce longitudinal movement of the pinion.
- 10 17. An engine starter drive including a rotatable shaft, a supporting shaft therefor, a driving member mounted on a rotatable shaft for longitudinal movement thereof and rotary movement therewith and also sup-
- 15 ported by such supporting shaft, said driving member comprising a pinion mounted to slide on the supporting shaft, a hollow extension mounted on the rotatable shaft, and a disk portion intermediate such pinion and extension and a plurality of pins mounted 20 radially in such disk portion and cooperat-
- ing with said supporting shaft to enforce longitudinal movement of the pinion.
18. An engine starter drive including a rotatable shaft, a supporting shaft therefor, 25 a driving member mounted on a rotatable shaft for longitudinal movement thereof and rotary movement therewith and also supported by such supporting shaft, said driving member comprising a pinion mounted 30 to slide on the supporting shaft, a hollow extension mounted on the rotatable shaft, and a disk portion intermediate such pinion and extension, a cylinder inclosing such drive and operatively connected with the rotatable shaft, and means mounted in such disk portion and coöperating with the supporting shaft to enforce longitudinal movement of the pinion, and also coöperating 35 with the cylinder to hold the pinion retracted 40 when rotating in disengaged position.

WILLIAM L. McGRATH.
